COMBINED PUBLIC TELEPHONE ENCLOSURE AND SUPPORT

Keith David Bartley and Fred Arlington Dewhirst, Indianapolis, Ind., Donald Michael Genaro, Haworth, N.J., and John Niel McGarvey, Drexel Hill, Pa., assignors to Bell Telephone Laboratories, Incorporated, Murray Hill, N.J.

Original design application June 5, 1972, Ser. No. 260,064. Divided and this application Aug. 20, 1973, Ser. No. 390,109

Term of patent 14 years

Int. Cl. D25—99

U.S. Cl. D13—1 L

FIG. 1

FIG. 2

FIG. 3

FIG. 4

FIG. 1 is a perspective view of our new design for a combined public telephone enclosure and support wherein the support is free standing and includes an enclosure for the public telephone;

FIG. 2 is a reduced rear view of the support;

FIG. 3 is a front view of the support; and

FIG. 4 is a side view of the support, the opposite side being substantially a mirror image thereof.

The broken line portions are shown for illustrative purposes only and do not comprise part of the design.

This application is a division of our copending application, Ser. No. 260,064, filed June 5, 1972.

We claim:

The ornamental design for a combined public telephone enclosure and support, substantially as shown and described.
